DESIGN FOR A SPECTACLE FRAME

Georges Bolle, Church Way, Wellingborough, England, assignor to Thurgar Bolle Limited, Church Way, Wellingborough, England, a British company

Application June 16, 1947, Serial No. 139,704

Term of patent 14 years

(Cl. D57—1)

To all whom it may concern:

Be it known that I, Georges Bolle, a French citizen, residing at Orient House, Church Way, Wellingborough, Northamptonshire, England, have invented a new, original, and ornamental Design for a Spectacle Frame, of which the following is a specification, reference being made to the accompanying drawings, forming part thereof.

Fig. 1 is a front perspective view of a spectacle frame, showing my new design;

Fig. 2 is a rear perspective view thereof;

Fig. 3 is a side elevational view; and

Fig. 4 is a fragmentary sectional view taken on line A—B of Fig. 3.

I claim:

The ornamental design for a spectacle frame, as shown.

GEORGES BOLLE.
